LOW POWER MINIATURE FLUORESCENT AND/OR GLOW LAMP

Filed Nov. 8, 1943

UNITED STATES PATENT OFFICE

2,476,616

LOW-POWER MINIATURE FLUORESCENT
AND/OR GLOW LAMPChalmers Morehead, East Orange, N. J., assignor
to Westinghouse Electric Corporation, East
Pittsburgh, Pa., a corporation of Pennsylvania

Application November 8, 1943, Serial No. 509,350

6 Claims. (Cl. 315—58)

1

This invention relates to negative glow lamps of small power which may also be used as fluorescent lamps.

The primary object of my invention, generally considered, is to produce a low wattage glow lamp operable on household alternating or direct current, and the envelope of which, if desired, may be coated with fluorescent material to increase the visible light output.

Another object of my invention is to produce a lamp which contains electrodes, desirably forming extensions of the lead-in conductors, helically coiled and closely interspaced with respect to one another, said lamp having a gaseous filling, said electrodes being coated with electron-emission material, and the lamp operable with a power consumption of the order of .1 watt.

A further object of my invention is to provide negative glow lamps of the gaseous conduction type where the cathode and anode are closely spaced to provide very short arc lengths, caesium being provided to reduce the ionization potential, and a large resistance being incorporated in the lamp base to cut down the current flow to a very small amount.

A still further object of my invention is to provide a negative glow lamp in which the gaseous filling surrounding the electrodes comprises neon and krypton in such proportions that the generated radiation has an effect on fluorescent material similar to that of 2537 A. U. wave length.

An additional object of my invention is to provide a negative glow lamp of the gaseous conduction type containing electrodes to which is applied caesium for lowering the ionization potential.

Another object of my invention is the provision of a negative glow lamp of the gaseous conduction type containing small closely-spaced wire electrodes in a small envelope, the interior surface of which is coated with beryllium-free manganese-activated zinc silicate containing an excess of zinc.

Other objects and advantages of the invention, relating to the particular arrangement and construction of the various parts, will become apparent as the description proceeds.

Referring to the drawings:

Figure 1 is an elevational view of a lamp with a bayonet-type base, shown to scale and full size in the original drawing, and embodying my invention.

Figure 2 is an elevational view of a lamp with a miniature screw-threaded base, shown to scale

2

and full size in the original drawing, and embodying my invention.

Figure 3 is an axial sectional view, of the lamp of Figure 2 showing the details, including the base-bulb connection by cement, to scale and enlarged.

Figure 4 is a transverse sectional view on the lines IV—IV of Figure 3, in the direction of the arrows.

10 Figure 5 is a transverse sectional view on the line V—V of Figure 3, in the direction of the arrows.

Figure 6 is a circuit diagram illustrating one use of my lamp.

15 Figure 7 is a circuit diagram illustrating another use of my lamp.

The present application relates to one of the new lamps which has been developed by reason of the war. It may have an envelope no larger than an ordinary marble and yet be of remarkable efficiency. If of the fluorescent type, it is adapted to give off more light than a $\frac{1}{4}$ watt neon glow lamp that consumes $2\frac{1}{2}$ times as much power. It is believed to be the first instance of high efficiency achievement with a modern fluorescent lamp in a miniature size. The energy economy is such that thirty of the lamps need no more than an ordinary electrical clock motor, thereby making such suitable for many military

20 applications where a light indication is required and very little energy available. For example, one of these lamps might be used to mark a cache of supplies left unattended for months, using energy from dry cells. One could be used 25 as a flashing lamp on life rafts. If made available after the war for household use, a lamp could be left burning constantly for six months to mark a stair step or key-hole, for an insignificant amount of electricity.

40 Referring now to the drawings in detail, like parts being designated by like reference characters, and first considering the Figures 1 to 5, inclusive, there is shown as one embodiment of my invention, a lamp 11 in Figure 1, and as

45 another embodiment, a lamp 11^a in Figures 2 to 5, inclusive, said lamps being adapted for operation on about 100 volts A. C. or 140 volts D. C. and identical except that the lamp of Figure 1 has a bayonet-type base 12 and desirably has no base-contained resistor, while that of said other figures has a screw-threaded miniature type base 12^a desirably containing a resistor 13 in series with one of the leads 14 and prevented from electrically contacting the shell of said base by suitable insulation, such as a paper sleeve

29. Said resistor may be a tiny ring of carbon-impregnated insulating material, so that its resistance, when used as illustrated, that is, where the circular arc portions are in parallel, is about 30,000 ohms or from 25,000 to 35,000 ohms.

The envelope 15 is desirably of the miniature spherical type, say about $\frac{3}{4}$ " in diameter, and contains a mount 16. The mount is very simply made, as by fastening the ordinary dumet leads 14 and 17 together with a bead 18 of glass, and coiling the end portions beyond said bead into interspaced helical form, as indicated at 19 and 21, so that they lie within about 2 mm. from each other. These helical portions are to form the electrodes, and for that purpose, they are, at least one, but desirably both coated from the bead 18 to their ends with a mixture, indicated at 22 and 23, adapted to develop electron-emission material in the form of free caesium on heating, for the purpose of lowering the ionization potential. For that purpose, the mixture desirably consists of potassium dichromate $K_2Cr_2O_7$, and caesium dichromate $Cs_2Cr_2O_7$, with an admixture of metallic magnesium as a reducing agent. The envelope 15 is desirably filled with a mixture of rare gases, such as 4 parts of neon and 1 part of krypton, by volume, with or without a trace of argon, say a small percentage of the order of $\frac{1}{2}\%$, and/or xenon, at a pressure desirably between 12 and 30 mm., but even between 10 and 40 mm. of mercury. In order to make it possible to use a liquid air trap on the exhaust system, when the evacuated lamps are filled with the gas mixture, without loss of krypton through condensation, the partial pressure due thereto should not exceed 4 mm. With this consideration, the optimum gas mixture, consists of 4 parts of neon to 1 part of krypton, by volume, used at a pressure of about 20 mm.

Glow lamps with the above gas mixture, either with or without a fluorescent coating, will operate satisfactorily over a wide range of ambient temperatures and at currents of the order of .001 ampere. The gas mixture results in a lower break-down voltage than if krypton alone were used. It is not objectionable if the krypton contains some xenon. After gas filling, sealing-in and seasoning as by running at over-voltage, say 220 volts A. C. for about an hour, to develop the metallic caesium electron-emission material by chemical reaction, the lamp is assembled with a conventional base, with or without a resistance element as illustrated in Figure 3. Said resistance element 13, if used, desirably fits over the exhaust tip 24, and the desired lead to which said resistance element 13 is connected being, therefore, that which goes to the center contact 25, as distinguished from the shell 26.

If a fluorescent lamp is to be made of the device previously described, the interior surface of the bulb 15 is coated with a phosphor, which desirably consists of beryllium-free manganese-activated zinc silicate with an excess of zinc. No other qualification other than that it passes through a 100-mesh sieve is required. This particular phosphor is found to be more efficient for changing the ultra violet radiations, generated by the discharge between the electrodes, into visible radiations of a greenish hue. However, if desired, other phosphors may be employed, as to provide other color effects.

If connected directly across a source of continuous power, a series resistance is necessary in order to control the current flow after the initial gas break-down. However, if flashes, rather than

continuous light, are desired, a circuit such as shown in Figure 6 is desirably employed. In accordance with this circuit a lamp 11 is used across a source 27 of direct current, in series with a resistor 28 of desirably about 1 megohm capacity. Across the lamp leads, a condenser 29 is applied, desirably of a capacity of $\frac{1}{2}$ to 1 microfarad. If the flash is to be extended, a small resistance 31, of say about 500 ohms, may also be used between the condenser and lamp, as indicated, although this is not essential. In operation, the condenser 29 will slowly charge through the large resistor 28 until the break-down voltage of the lamp 11 is reached. When the condenser 29 becomes sufficiently recharged, the spacing of the flashings may therefore be controlled by controlling the value of the resistor 28, shown adjustable.

Referring now to Figure 7, an arrangement is there shown where a series of lamps 11^a may be operated in parallel, as on an Xmas tree, for example, from a low-power low-voltage source 32 which may be an ordinary automobile storage battery or a few dry cells. This particular source is connected through a vibrator 33, such as one of those used on automobiles for generating the B-power for the radio, and from there to the primary winding 34 of a step-up transformer 35, across the secondary winding 36 of which are the lamps 11^a in parallel. The low voltage direct current is, by this arrangement, broken up into intermittent current which is in turn transformed to alternating current of the desired potential, of say about 100 volts.

From the foregoing description it will be seen that I have developed an efficient low power source of light, which may take the form of a glow lamp or a fluorescent lamp of small size operable from a convenient source of power.

Although preferred embodiments of my invention have been described, it will be understood that modifications may be made within the spirit and scope of the appended claims.

I claim:

1. A negative-glow lamp of the gaseous conduction type, comprising closely-spaced electrodes functioning as cathode and anode, an enclosing envelope, electron-emission material disposed on at least one of said electrodes to lower the ionization potential, and a gaseous filling in said envelope consisting of neon and krypton, in the proportion of about four parts of the former to one of the latter, by volume, whereby the generated radiations have an effect on fluorescent material consisting of beryllium-free, manganese-activated zinc silicate with an excess of zinc, similar to that of radiations of 2537 A. U. wavelength, the interior of said envelope being coated with the mentioned fluorescent material for the development of visible light from said radiations.

2. A negative-glow lamp of the gaseous conduction type, comprising closely-spaced electrodes functioning as cathode and anode, an enclosing envelope, electron-emission material disposed on at least one of said electrodes to lower the ionization potential, and a gaseous filling in said envelope comprising essentially a preponderance of neon and a smaller proportion of krypton whereby the generated radiations have an effect on fluorescent material consisting of beryllium-free, manganese-activated zinc silicate with an excess of zinc, similar to that of radiations of

2537 A. U. wavelength, the interior of said envelope being coated with the mentioned fluorescent material for the development of visible light from said radiations.

3. A negative glow lamp of the gaseous conduction type comprising an enclosing envelope about three quarters of an inch in diameter, leads sealed through the outer wall thereof, internally held together and braced by a glass bead, and terminating in interior helical closely-spaced electrodes, a mixture on at least one of said electrodes for developing metallic caesium, a gaseous filling in said envelope consisting of about four parts neon and one part krypton, by volume, at a pressure of about twenty millimeters of mercury, the interior of said envelope being coated with phosphor consisting of beryllium-free, manganese-activated zinc silicate with an excess of zinc, for the purpose of changing the generated radiations impinging thereon to visible light, said envelope being tipped-off adjacent the points of entry of the leads, a ring-shaped resistor fitting over the tip so formed and with one terminal connected to one of said leads, a lamp base enclosing said tip and resistor, and a connection from the other terminal of said resistor to the center contact of said base.

4. A negative glow lamp of the gaseous conduction type comprising electrodes functioning as cathode and anode, an enclosing envelope the interior surface of which is coated with fluorescent material consisting of beryllium-free manganese-activated zinc silicate with an excess of zinc, electron-emission material disposed on at least one of said electrodes to lower the ionization potential, and a preponderance of neon and a smaller proportion of krypton in said envelope, whereby the generated radiations have an effect on said fluorescent material similar to that of radiations of 2537 A. U. wave length, to provide for the efficient development of visible light.

5. A negative glow lamp of the gaseous conduction type comprising an enclosing envelope about three quarters of an inch in diameter, the interior of said envelope being coated with phosphor consisting of beryllium-free manganese-activated zinc silicate with an excess of zinc, leads sealed through the envelope outer wall and terminating at closely spaced electrodes, a mixture on at least one of said electrodes for developing metallic caesium, a preponderance of neon and a smaller proportion of krypton at a pressure between 12 and 30 millimeters of mercury, in

said envelope, whereby the generated radiations have an effect on said phosphor similar to that of radiations of 2537 A. U. wave length, to efficiently generate visible light, said envelope being tipped off at a point adjacent said leads, a ring-shaped resistor fitting over the tip so formed and with one terminal connected to one of said leads, a lamp base with a center contact and enclosing said tip and resistor, and a connection from the other resistor terminal to the center contact of said base.

6. A negative-glow lamp of the gaseous conduction type comprising closely spaced electrodes functioning as cathode and anode, an enclosing envelope, electron-emission material disposed on at least one of said electrodes to lower the ionization potential, and a gaseous filling in said envelope comprising essentially a preponderance of neon and a smaller proportion of krypton, at a pressure between 12 and 30 mm. of mercury, whereby the generated radiations have an effect on fluorescent material consisting of beryllium-free, manganese-activated zinc silicate with an excess of zinc, similar to that of radiations of 2537 A. U. wavelength, the interior of said envelope being coated with the mentioned fluorescent material for the development of visible light from said radiations.
